FUEL BURNING DEVICE

John S. Skelly, Monongahela, Pa., assignor to
 Combustion Engineering Company, Inc., a corporation of Delaware

Application February 15, 1932, Serial No. 592,929

10 Claims. (Cl. 110—47)

This invention relates to boilers forming part of heating systems for homes, apartment houses, and the like, and more particularly to stokers therefor.

5 The cost of fuel with heating boilers, depends largely upon the adaptability of the fuel to control in its rate of delivery to the boiler and in the distribution thereof over the fire bed area and the cost of the fuel as such.

10 Certain types of fuel, gas and oil, for example, are much more desirable for heating purposes than solid fuels, as coal or coke, because the burner mechanisms are so easily adaptable to remote control in accordance with the temperature desired to be maintained at some point more or less remote from the furnace and its burners. Such fuels are, of course, expensive in comparison to the cost of fuels, such as soft coal; but, even so, have been more desirable because the 20 rate of combustion of gas and oil may be more accurately and conveniently handled.

There are always available on the market various grades of coal, and of these grades, slack, as it is generally called, has practically no market 25 value and is, therefore, very inexpensive even though its heating qualities are practically the same as of the better grades of coal.

Therefore, if the proper furnace mechanism were available, such as could be easily regulated 30 and controlled from a remote point, these practically unmarketable grades of coal could be used with complete satisfactory results and substantial savings realized.

An object of this invention is the provision of 35 a stoker for burning coal that may be designed for use with heating boilers now in use or as a standard part of such boilers.

Another object of this invention is the provision 40 of a stoker by means of which coal fuel may be burned efficiently and economically, easily adapted for remote control to obtain uniform heating effects, and capable of burning finely divided coal which ordinarily has practically no market value.

45 A further object of this invention is the provision of a stoker in which coal may be delivered uniformly to and evenly distributed over the fire bed in order to obtain efficient and economical combustion.

50 A still further object of the invention is the provision of a simple inexpensive and efficient screw-type underfeed stoker.

In the screw-type of underfeed stoker, if the screw extends a considerable distance into the 55 retort to obtain uniform coal distribution, heavy

overhanging bearings are required to prevent the screw from rising, and such bearings create friction and increase the power necessary to operate the same.

If the screw extends only a short distance into the retort it is impossible to secure equal distribution of the coal throughout the full length of the retort and the full burning area thereof.

In either case, the screw feed stoker does not provide the necessary disturbance or agitation 10 of the fuel bed to burn coking and caking coals successfully, and for this reason the sliding bottom, pusher and plunger types of stoker are most generally used.

For use in heating boilers, where head room, simplicity of installation and control are important factors, the screw feed stoker is most practical.

An object of this invention is therefore to provide a stoker having the combined attributes and 20 advantages of the screw feed stoker and the sliding bottom, pusher and plunger types of stoker, without their inherent disadvantages.

Other objects of the invention will, in part, be apparent and will, in part, be obvious to those skilled in this art from the following description taken in conjunction with the accompanying drawings; in which:

Figure 1 is a view in longitudinal vertical section of a stoker arranged and constructed in accordance with an embodiment of the invention;

Fig. 2 is a view in section taken on line II—II of Figure 1;

Fig. 3 is an enlarged fragmentary view in section of a detail embodied in the device shown in Fig. 1;

Fig. 4 is an end view of a modified form of cam detail adapted for use in the stoker of Figure 1;

Fig. 5 is a view in side elevation, partly in section, of the cam detail shown in Fig. 4;

Fig. 6 is a view in perspective of a pin for supporting cam rollers embodied in the mechanism shown in Figs. 4 and 5;

Fig. 7 is a fragmentary view in section taken on line VII—VII of Fig. 2, showing the construction and arrangement of elements forming the twyer of the stoker;

Fig. 8 is a top plan view of a detail forming part of the fuel distributing and agitating means embodied in the stoker; and

Fig. 9 is a fragmentary view, similar to Fig. 1, showing a modified form of stoker embodying the invention.

Throughout the drawings and the specification, like reference characters indicate like parts.

The stoker embodying the present invention is adapted for use in heating boilers for homes, apartment houses and the like, and designed to burn various grades of fuel, efficiently. Such a 5 stoker may be controlled automatically so that the rate of combustion may be effectively regulated to suit the requirements for heat.

The particular stoker illustrated comprises a retort 1 to which coal is fed by means of a screw 10 2, and a movable member 3, operating in the retort, having auxiliary distributors or agitators 4 thereon arranged to rake and distribute the coal uniformly over the retort area and to agitate the fire bed.

15 As shown in the drawings, the retort is disposed in an air chamber 5 to which air for combustion is supplied under pressure. The retort and air chamber are designed to be disposed in a furnace (not shown) in such position that the fire bed in the retort is near to or slightly below the water line of the heating boiler, in case the heating 20 system is of the hot water, steam or vapor type.

Fuel, such as coal, in a relatively finely divided 25 state is fed to the retort, as required, by means of the screw 2 which is disposed in a screw housing 6. The screw may be driven by a motor M, preferably an electric motor, the operation of which may be controlled from a remote point (by 30 means of a thermostat or equivalent means) where it is desired to maintain the temperature constant at some predetermined value. The motor M drives a fan F which supplies forced draft, or air under pressure to the air chamber 5.

35 The retort, as shown in Fig. 2, is substantially U shape in transverse section, having an open top and closed bottom. The forward end of the retort is closed by means of an upwardly inclined wall 7, and the rearward end thereof terminates in a tubular portion 8 having a flange 9 adapted to register with the flanged end of the feed screw housing 6.

The retort may be cast either as a single integral unit or it may be made up from a plurality 45 of cast sections such as a, b, and c placed end on end as shown in Fig. 1.

The chamber 5 comprises a bottom plate 10, vertically disposed side plates 11 and end plates 12 and 13. The sides of the bottom plate may be 50 flanged upwardly, as shown at 14, and the side plates bolted to these flanges as indicated.

In order that the retort may be spaced from the bottom plate of the air chamber, depending lugs 15 are formed on the bottom thereof which 55 rest on the bottom plate. To provide for holding the retort in the proper position, the bottom plate is provided with upwardly extending lugs 16 between which the depending flanges of the retort are disposed.

60 In order that air for combustion may be directed into and across the top of the retort where combustion takes place, a twyer 17 preferably hollow is provided.

The twyer bridges the space between the side 65 and end walls of the retort and air chamber and is supported thereon. Thus, the twyer, in conjunction with the retort, forms a closure, cover, or roof for the air chamber.

The twyer is preferably made up from a plurality 70 of sectional and removable twyer blocks 18 and 18', the latter being placed at the ends of the retort. As shown, each twyer block has a top wall 19, a side wall 20, a front wall 21, in which openings 22 are formed and through which air flows to the fuel or fire bed at a point directly

above the top of the retort, and an open bottom.

The outer ends of the twyer blocks 18 rest on flanges 23 formed at the upper edges of the air chamber side walls 11 and the outer ends of boxes 18' rest on flanges 23'. In order to hold the twyer blocks in position, the outer ends thereof may be provided with lugs 24 which register in openings or apertures 25 formed in flanges 23. The inner ends of the twyer blocks may be formed with hook shaped portions 26 which overhang the sides of the retort. 10

The twyer blocks, as shown, are open at their bottom side and at one of the vertical sides, but when mounted in position as shown in Fig. 7, the open side of each twyer block is closed by 15 the side wall 20 of an adjacent twyer block, thereby forming a plurality of parallel disposed passageways 27 which communicate with the air chamber. As shown in Fig. 1, the openings 22 in the front wall of the twyer blocks are aligned 20 and separated from each other by the intervening side walls 20.

The fuel to be fed to the retort 1 may be stored in a hopper 28 having an open bottom which is disposed over a housing 29 in which the forward 25 end of the feed screw 2 operates. The feed screw lies in the bottom of the housing and is mounted in a bearing 30 secured in a side wall 31 thereof. The opposite side wall of housing 29 has an opening 32 through which the screw projects into 30 the feed screw housing 6. As shown, the feed screw housing is secured to housing 29 and to end wall 13 of the air chamber 5 so that it will be held in the proper operating position and in alignment throughout its full length. 35

Since the feed screw is driven at a relatively low speed, one or two revolutions per minute for example, the screw is driven from motor M through a speed reducer or gear reduction mechanism 34 of any standard design suitable for the 40 purpose. The power take-off shaft 35 of the speed reducer is coupled to the feed screw as indicated at 36.

In order that air for combustion may be introduced to air chamber 5, the feed screw housing is 45 enclosed in a casing 37 which may be bolted or otherwise secured to the hopper housing 29, the wall 13 of the air chamber, and the base 38 on which the hopper housing, the motor, and speed reducer mechanism are mounted. The air delivered to the interior of the casing 37 therefore flows around or on all sides of the feed screw housing and enters the air chamber 5 through an opening 40 which surrounds the tubular portion 8 of the retort. The air chamber being thus supplied with air under pressure, air for combustion will be discharged uniformly through the twyer block openings 22 to all parts of the fire bed. 55

As shown in Fig. 1, the feed screw 2 terminates at the entrance to the retort and is confined almost wholly within the housing 6. Therefore, the fuel delivered to the retort is pushed forwardly by the coal entering behind it from the feed screw. If the retort extends for a substantial distance from the free end of the feed screw, it will 60 be apparent that there will be a tendency for the fuel to accumulate or pile up at a certain point, resulting in uneven distribution of the fuel throughout the retort area.

In order to secure uniform distribution of 70 the incoming fuel to all parts of the retort, and also to secure agitation of the fire bed, the movable member 3 is given a reciprocating motion. The member 3 with its member 4, while reciprocating, rakes the fuel to and fro in the 75

retort causing the same to be uniformly distributed throughout the length of the retort and over its fuel burning area, and prevents piling up of the fuel at different points longitudinally of the retort. Since members 4 extend upwardly from member 3, the fire bed will be agitated sufficiently to prevent caking of the fire bed. Member 3 with its agitating or raking members 4 thus, in effect, functions as a sliding bottom.

Member 3 may comprise a bar somewhat triangular in transverse section with the apex of the triangle disposed lowermost. The forward end of the bar extends through an opening in the upwardly inclined wall 7 of the retort which is lined with wear resisting member 42. The rearward end of the bar extends through an opening in a wall 44 of the retort at a point immediately above the tubular portion 8 thereof. In order that the bar may have support at its middle portion, supporting flanges or lugs 45 and 46 are provided, the outer ends of which rest on pads or lugs 47 formed integrally with the side walls of the retort.

The distributing and agitating members 4, as shown in Fig. 8, comprise a base 48 having an upwardly extending transverse web or vane 49 and a stiffening rib 50 that runs lengthwise along the middle of the base.

Since bar 3 runs lengthwise and at the middle of the retort, the incoming fuel will be divided by the wedge-like bar and caused to move upwardly on each side thereof along the side walls of the retort. As the fuel moves upwardly along the side walls of the retort, the agitating and distributing members 4 move or rake the fuel back and forth to secure the desired distribution and agitation of the fuel bed.

In order that the agitating and distributing mechanism may be reciprocated when the feed screw is operating, bar 3 is coupled by means of a connecting rod 51 to a cam 52. The cam, as shown, is mounted on the power take-off shaft 35 of the speed reducer mechanism so that as the shaft turns, the cam will reciprocate the connecting rod 51 and the agitating and distributing bar 3 while the feed screw is operating.

The particular form of cam shown may comprise a wheel, disc, or block 53 having a continuous groove 54 formed in the periphery thereof for the reception of a cam follower or roller 55 carried by a pin 56 extending through the end of the connecting rod, as shown in Fig. 1. Fig. 3 shows more clearly the form of the groove in the wheel 53, the roller 55 and the pin 56 by which it is attached to the connecting rod.

The groove 53 has straight sides disposed at substantially right angles to the axis of shaft 35 so that roller 56 may run freely therein without binding. As is apparent by inspection of Fig. 1, groove 53 is contained in a plane which is disposed at an angle to the axis of shaft 35, so that as member 53 turns, rod 51 and bar 3 will be given reciprocating motion to affect the result desired.

In the operation of a stoker such as shown in Fig. 1, it may be necessary at times to vary or adjust the stroke of the agitating and distributing bar 3 in order to secure proper distribution of the fuel and the most efficient combustion thereof. When such adjustment is desired, a cam mechanism such as shown in Figs. 4 and 5 may be utilized.

The mechanism shown in Figs. 4 and 5 comprises a hub 58 adapted for mounting on the power take-off shaft 35 of the speed reducer having a wobble plate 59 thereon. The rim of the wobble plate is preferably straight sided so that cam rollers or followers 60 and 61, mounted on the connecting rod 51 may roll freely on the rim without binding.

In order that the throw of the connecting rod may be adjusted to thereby regulate the stroke 10 of the agitator bar 3, one or the other, or both, of rollers 60 and 61 may be adjustably mounted on the connecting rod. As shown, only one of the rollers is made adjustable lengthwise of the connecting rod; namely, roller 60. As shown, 15 roller 60 is mounted on a pin 62 which has a square or polyhedral portion 63 adapted to be received in a slot 64 formed on the connecting rod. The upper portion of the slot is partially closed by flanges 65 spaced apart sufficiently to 20 accommodate the screw thread portion of the roller pin. Thus, the pin may be moved longitudinally of the slot either away from or towards the wobble plate and the pin secured in place, by means of a nut 66. The nut, when tightened, 25 clamps the overhanging flanges 65 between the shoulder on the pin and a washer 67, thereby securing the roller pin positively in position. A set screw 68 may be utilized to assist in making the adjustment and to act as a stop for the 30 roller pin in one direction.

It will be apparent that when both of the rollers 60 and 61 contact at all times with the rim of the wobble plate, the stroke of the agitator bar will be equal to the throw of the cam; 35 and that if the rollers are separated a distance greater than the width of the rim, the throw of the agitator bar will be less than the throw of the cam. Therefore, the farther the rollers are separated from each other, the shorter will be 40 the throw of the agitator bar. In practice, the throw of the agitator bar may be so adjusted as to insure the proper distribution of the coal throughout the length of the retort and the proper agitation of the fire bed. 45

To avoid bridging of coal across the throat of the hopper housing and the consequent interruption in the feed thereof to the retort, the connecting rod 51 may be provided with an agitator arm 69 that extends upwardly towards the 50 bottom of the hopper 28. As the connecting rod reciprocates, arm 69 continually agitates the coal coming from the hopper and prevents the same from bridging, thereby assuring a continuous 55 feed of coal to the feed screw.

The operation of the stoker mechanism disclosed in Fig. 1 is substantially as follows: The hopper and the retort having been filled with coal, waste or kindling is thrown on the coal in the retort and ignited. The burning waste 60 or kindling will set fire to the coal and when combustion is well established the motor may be started. When the motor is set in operation the feed screw delivers fresh coal and the fan supplies the air chamber with air under pressure. 65 The air from the air chamber flows through the openings in the twyer boxes to the fire bed, causing the fuel to burn rather vigorously. The fresh fuel is forced upwardly through the retort to replenish the fuel bed. 70

The fresh coal underlying the fuel bed cokes before combustion takes place, but in the coking process, volatile matters are driven off and burned as they pass through the fire bed. Thus, the most useful combustible ingredients are burned before 75

the coke residue reaches the fire bed proper. Efficient combustion of the coal is, therefore, attained. Since the volatile matters are burned as they pass through the fire bed, soft coal may be burned without causing an objectionable amount of smoke to be emitted. In fact, by properly adjusting the rate of delivery of air and fuel, the smoke emitted from the furnace will be practically unnoticeable.

10. As the combustion process continues, the ashes are discharged over the sides of the top of the twyer blocks and collected on the top walls thereof. As these walls slope downwardly, the ash if it piles up, will fall periodically towards the air 15 chamber side walls 11, and may be swept off with a scraper of some sort and removed from the furnace, as required.

While, in Fig. 1, the feed screw is shown as being disposed below the level of the pusher and distributor bar 3, it may be desirable to mount the feed screw at a higher level as shown in Fig. 9, for example. The feed screw housing 6 of the stoker in Fig. 9 is coupled to the retort 1 at a higher level than in Fig. 1, thereby providing room or space 20 below the same for a raking or distributing bar 11 and a connecting rod 72. The connecting rod, of course, would run under the hopper housing 29 and be coupled to the cam 52 to give the bar the reciprocating motion described in connection with 25 Fig. 1. The bar 11 carries distributing and agitating members 4, such as shown in Figs. 1 and 8.

The agitator and distributor bar 11, as shown, is disposed longitudinally of the retort with one end extending through the upwardly sloping wall 35 1 thereof. A bearing plate 73, secured to the retort wall 1 has a wear portion 74 located within the opening to resist upward thrusts of the bar and to protect the sloping retort wall against the 40 wearing action which would otherwise result between the wall and the bar. The wear portion 71 when worn may be removed and replaced.

Since the air chamber in which the retort is disposed, and the twyer, which is made up of individual twyer blocks of the stoker in Fig. 9 are 45 substantially the same in all essential particulars as in the stoker of Figure 1, similar and corresponding parts are designated by the same reference characters.

In the stoker of Fig. 9, coal, in a finely divided 50 state, is fed by the feed screw into the retort on top of the pusher and distributor bar 11. Since the bar reciprocates when the feed screw is in motion, the coal delivered to the retort is raked back and forth so as to maintain the thickness of the coal substantially uniform throughout the 55 full length of the retort. The pusher bar with its distributing elements in addition to providing uniform distribution of coal also agitates the fuel bed to prevent caking of the coal at the top of the retort, thereby insuring that combustion will take place efficiently and rapidly. In all other respects, the stokers of Figs. 1 and 9 operate in substantially the same manner.

The stoker motor M may be controlled by 60 means of a thermostat located at some convenient point at which it is desired to maintain the temperature at some predetermined value. Since thermostatic mechanisms suitable for this purpose are well known in the art and available on the market, it is believed unnecessary to illustrate such devices herein. These devices are mentioned merely to show that the stoker herein disclosed is adapted to be started and stopped according to the requirements for heat so that only

so much fuel will be burned in the furnace as is required to satisfy the demand for heat.

It will be apparent to those skilled in this particular art that the stokers herein shown admit of various modifications and changes without departing from either the scope or the spirit of the invention. It is desired therefore that only such limitations shall be placed on the invention as are imposed by the prior art and the appended claims.

What I claim as new and desire to secure by 10 Letters Patent is:

1. In a stoker, the combination with a container adapted to contain coal, and a retort in which coal may be burned adapted for mounting in the combustion chamber of a furnace, of a screw conveyor for feeding coal from the container to the retort, and a horizontally reciprocating member in said retort having means thereon to distribute the coal uniformly throughout the retort area and to agitate the fire bed. 15

2. In an underfeed stoker, the combination with a container adapted to contain coal, and a retort in which coal may be burned adapted for mounting in the combustion space of a furnace, of a feed screw housing connecting said retort 20 and container, a screw in said housing having its discharge end terminating at the entrance to the retort, a horizontally reciprocating member disposed in the retort having a raking element thereon projecting upwardly towards the top of the 25 retort and disposed in the path of movement of the coal delivered by the screw to the retort, said element as it moves back and forth with the reciprocating member, raking and distributing the coal throughout the retort area, and means for 30 operating the screw and reciprocating member.

3. An underfeed stoker unit comprising an air chamber having a retort therein, the retort having an open top, a screw feeder for delivering fuel through an opening in one end of said stoker, 40 and a reciprocating member having vertically disposed vanes thereon adapted to distribute the fuel, delivered by the screw, uniformly throughout the fuel receiving space of the retort.

4. An underfeed stoker unit comprising an air 45 chamber having a retort therein, the retort having an open top, a screw feeder adapted to deliver fuel through an opening in one end of said retort, a reciprocating member having vertically disposed vanes thereon adapted to distribute the 50 fuel delivered by the screw uniformly throughout the fuel receiving space of the retort, and a hollow twyer located at the top of the retort along the border thereof, the interior of said twyer being in communication with said air chamber, 55 there being openings in the twyer through which air may flow and be directed across the top of said retort.

5. A stoker adapted for mounting as a unit in operative relation to a furnace comprising a box, 60 a retort of trough-shape mounted in spaced relation to the bottom, side and end walls of the box, the forward end wall of the retort sloping upwardly at an acute angle from the bottom of the retort, a twyer mounted on the tops of the side 65 and end walls of the retort and box, thereby forming a closed space about the retort into which air may be directed under pressure, the twyer being provided with openings disposed around the top of the retort through which air 70 may discharge in a direction across the top of same, an agitator and distributor bar mounted for reciprocating motion along the bottom and longitudinally of the retort, a screw conveyor 75 disposed to deliver fuel to the retort at a point

- located above the bar, and means for driving the conveyor and reciprocating the bar.
6. In combination in an underfeed stoker, an open top retort having a fuel receiving opening at one end thereof and below the upper edges thereof, twyer blocks associated with said retort, said blocks constituting a vertical extension thereof and providing fuel supporting surfaces on either side thereof, a hopper removed from said retort, a screw for delivering fuel from said hopper to said retort through said fuel receiving opening, agitators located within said retort below the upper edges thereof and means for rotating said screw and for reciprocating said agitators longitudinally of the retort and in unison with the rotation of said screw to effect distribution of the fuel so delivered throughout the length of said retort and over said fuel supporting surfaces.
- 20 7. In combination in an underfeed stoker, a retort having a fuel receiving opening at one end thereof and below the upper edges thereof, fuel supporting and air delivering elements located adjacent said retort and constituting a vertical extension thereof, a fuel hopper removed from said retort, a screw for delivering fuel from said hopper to said retort through said fuel receiving opening, means for rotating said screw reciprocatory means located within said retort and movable back and forth longitudinally thereof to distribute and break up the mass of fuel delivered to said retort by said screw, and means for driving said screw and reciprocatory means in unison.
- 35 8. In combination in a stoker, an open top retort having a fuel delivery opening at one end thereof below the upper edges thereof, air delivery elements located around said retort and constituting an extension of the upper edges thereof, a fuel hopper removed from said retort, a screw for delivering fuel from said hopper to
- said retort through said fuel delivery opening, agitators located within said retort below the upper edges thereof and below the axis of said screw, and means for rotating said screw and reciprocating said agitators in unison with the rotation of said screw.
9. In combination with a stoker, an open top retort having a fuel delivery opening at one end thereof wholly below the upper edges thereof, air delivery and fuel supporting elements located around said retort and constituting a vertical extension thereof, a fuel hopper removed from said retort, a screw for delivering fuel from said hopper to said retort through said fuel delivery opening, fuel distributing mechanism disposed for movement lengthwise of and located within said retort and below the upper edges thereof, means for rotating said screw, and a cam driven by said means for reciprocating said mechanism within said retort and in unison with the rotation of said screw whereby fuel is delivered to the retort by the screw and distributed throughout the full length thereof by said distributing mechanism.
10. In an underfeed stoker, the combination of an elongated horizontally positioned retort, said retort being substantially U shaped in cross section, a fuel hopper positioned longitudinally of said retort and spaced from one end thereof, a horizontally positioned feed screw connecting said hopper and the adjacent end of said retort, said screw terminating adjacent the end of said retort nearest to said hopper and being positioned above the bottom of said retort, the end wall of said retort opposite to said screw sloping upwardly from the bottom of said retort, reciprocable feed means positioned on the bottom of said retort between the end of said screw and said sloping end wall, and means for simultaneously rotating said feed screw and reciprocating said feed means.

JOHN S. SKELLY. 40
